Primary Examiner — Dana K Weiland*Assistant Examiner* — David Michael Sullivan(57) **CLAIM**

The ornamental design for a smartphone, as shown and described.

DESCRIPTION

FIG. 1 is a front perspective view of a smartphone, showing an embodiment of our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a back perspective view thereof.

The broken lines in drawings show portions of the smartphone that form no part of the claimed design.

1 Claim, 6 Drawing Sheets(56)
